PNEUMATIC THREAD REMOVER

George N. Peterson, Worcester, Mass., assignor to Crompton & Knowles Loom Works, Worcester, Mass., a corporation of Massachusetts

Application March 8, 1950; Serial No. 148,375

22 Claims. (Cl. 139—256)

1

This is a continuation in part of my co-pending application Serial No. 102,547, filed July 1, 1949, now abandoned.

This invention relates to pneumatic thread removers for weft replenishing looms and one of the objects of the invention is to provide a remover so constructed that rebounding of the positioning or carrier part of the remover incident to movement to operating position will not materially effect correct location of the pick-up head of the remover relative to the thread to be removed.

In certain types of weft replenishing looms it is customary to use a pneumatic thread remover between the reserve bobbin magazine and the cloth for the purpose of removing the thread of the outgoing bobbin incident to a weft replenishing operation of the loom. As heretofore constructed these thread removers have been made with a rigid part held frictionally in thread pick-up operating position. The rigid part is moved from normal non-pick-up position to operating or pick-up position by the bobbin transfer arm, and since the latter moves rapidly the remover is likely to rebound upwardly and be held by the friction means in a position too high to catch the thread.

It is an important object of the present invention to provide a thread remover having a thread pick-up head and a positioner or carrier connected to each other by a resilient tube or the like which supports the head and can be bent or deformed on itself when the carrier moves to thread pick-up position so that if there should be upward rebounding of the carrier the tube, by tending to resume its normal shape, will hold the head down in correct position to pick up the thread.

In the operation of weft replenishing looms it occasionally happens that an improperly boxed shuttle will be in position to be struck by the thread remover when the latter tries to move to thread pick-up position. It is a further object of the invention to make the thread remover with an inherently resilient part which can yield upwardly under such conditions, and laterally if the shuttle should be in motion along the lay.

In previous patents, such as Nos. 2,475,987 and 2,482,690, I have shown thread removers which provide a slight air leakage or bleed when the remover is in normal position to prevent accidental removal of the thread. It is another object of the present invention to provide means causing a small jet of air leakage to enter one of

2

the tubes of the mechanism in such a direction as to set up a whirling stream of air which causes the thread to scrape and clean the tube of lint and dust drawn into the tube by subatmospheric pressures.

It is a further object of the invention to make one of the pneumatic tubes of the remover system serve as a bearing for another tube angularly movable on the first tube either to thread pick-up position or to non-pick-up position.

It is a still further object of the invention to provide the remover with conical bearing parts which are automatically kept in close engagement with each other to reduce air losses to a minimum.

With these and other objects in view which will appear as the description proceeds, the invention resides in the combination and arrangement of parts hereinafter described and set forth.

In the accompanying drawings, wherein two forms of the invention are set forth,

Fig. 1 is a side elevation of part of a weft replenishing mechanism having the preferred form of the invention applied thereto, part of the loom frame and the lay being shown in cross section and the remover being in its normal idle raised or non-pick-up position.

Fig. 2 is an enlarged plan view looking in the direction of arrow 2, Fig. 1.

Fig. 3 is an enlarged vertical section on line 3—3, Fig. 2.

Fig. 4 is an enlarged vertical section on line 4—4, Fig. 2, showing the parts in the positions they assume when the remover is in inactive or non-pick-up position.

Fig. 5 is similar to Fig. 4, but shows the parts in active or thread pick-up position.

Fig. 6 is a horizontal section on line 6—6, Fig. 4, the stationary tube being shown in plane.

Fig. 7 is an enlarged rear elevation of the thread remover head looking in the direction of arrow 7, Fig. 2.

Figs. 8 to 11 are diagrammatic views showing the thread remover in different positions, and

Fig. 12 is a view similar to Fig. 4, but showing a modified form of the invention.

Referring more particularly to Fig. 1, a loom frame 10 has secured thereto a support 11 provided with a pivot stud 12 on which is rockably mounted a magazine M which may be of the two-color type holding two stacks of reserve bobbins (not shown). The support 11 has a transfer arm stud 13 secured thereto on which is pivotally mounted a transfer arm 14. The latter is normally in the raised position shown in Fig. 1, but

when a weft replenishing operation of the loom occurs the transfer arm descends to move a reserve bobbin from the magazine M into the shuttle S which at that time is located in a shuttle box 15 on the lay 16. The lay has a race plate 17 across which extends a pad 18 preferably made of a pile fabric on which the thread T of the outgoing bobbin rests, see Fig. 2. This thread will ordinarily be severed by thread cutting mechanism (not shown) located adjacent to the delivery eye of the shuttle, and that part of the thread extending from the thread cutting mechanism back to the selvage will extend across the pad 18.

The matter thus far described is of common construction and of itself forms no part of the present invention except as noted hereinafter. The invention is not limited in its use to rocking magazines such as shown at M.

In carrying the preferred form of the invention into effect the loom frame 10 has secured thereto a small stand or support 20 held in vertically adjusted position on the loom frame by bolts 21 and having a pivot tube 22 secured thereto in angularly adjusted position by a set screw 23. A positioner or carrier member 25 has a hub 26 surrounding the tube 22, and a curved rigid preferably metallic tube 27 is secured in any desired manner to hub 26 and extends through the latter, see Fig. 4, so that an air passage 28 therein opens through a bearing surface 29 on the interior of hub 26. The tube 22 has attached to the right end thereof a hose or the like 30 which may be considered a source of subatmospheric pressures, since it is pneumatically connected to an exhaust pump (not shown), or other means for creating a partial vacuum within the tube 22 tending to move air through the tube in the direction of arrow a, Fig. 3.

The carrier 25 is provided with a lateral stud 31 extending into a slot 32 in the lower end of a depressing link 33 pivoted as at 34 to the transfer arm 14. This link 32 may be made of upper and lower parts 35 and 36, respectively, adjustably connected as at 37 so that the length of the link may be varied.

The tube 22 has a conical head 40 fitting the bearing 29 which is conical for the purpose. Tube 22 has a thread and air bore 41 extending longitudinally therethrough, the left end of the bore being enlarged and closed by a plug 42 which has a driving fit with but is removable from the head 40, see Fig. 3. A compression spring 43 is between the stand 20 and hub 26 of the carrier 25 and tends to hold the hub seated firmly on head 40.

The head 40 has a laterally opening port 44 extending therethrough and a shallow recess or air passageway 45 communicating with the port and extending circumferentially therefrom around part of the exterior surface 46 of the head 40.

Tube 27 serves as a carrier for a piece of resilient tubing 50 which is fitted over its rear end. Tube 50 may conveniently be made of soft elastic plastic or rubber. To the rear end of tubing 50 there is fitted a thread pick-up head 51 including a metal tube 52 extending into tube 50. A thread tongue or hook 53 is located rearward of the intake mouth 54 at the rear end of tube 52 and extends downwardly to a position below the mouth. Tongue 53 may be formed integrally with a thin metal shield plate 55 secured to the top of tube 52. The intake mouth is preferably long and narrow with its longer

dimension extending in the direction of the length of the lay. Tube 52 has an air passage 56 leading from the intake mouth 54 toward the carrier 25 and communicating with an air passage 57 in the resilient tube 50. While the head 51 has been described as made of metallic parts it is not necessarily thus made. The hub 26 and head 51, together with the parts between them, comprise a pneumatic thread remover designated at R, see Fig. 2, having an air and thread passage therethrough leading from mouth 54 to head 40.

A resetter 60 for the remover includes a flexible thong 61 secured at its rear end to the lay as at 62 and at its forward end to the carrier 25, as at 63.

In operation, the remover R will normally be in the raised idle position shown in Fig. 1 with the head 51 above the shuttle path. The tube 50, although elastic or resilient, is able to hold the head 51 in raised position when the carrier or positioner is in normal inactive or non-pick-up position. The spring 43 creates sufficient frictional engagement between bearing 26 and head 40 to hold the remover R in any position to which it may move. When a bobbin transfer occurs transfer arm 14 will descend and cause link 33 to rock the carrier 25 in a counterclockwise direction as viewed in Fig. 1 around tube 22 as a pivot against a stop 65 on stand 20. Descent of the remover will lower the elastic tube 50 and move head 51 against the lay to the position shown in Fig. 8. The link 33 is of such length that it will continue to lower the tube 22 after head 52 is in its lowest position, thereby stressing or bending the tube 50 to the deformed shape shown in full lines in Fig. 11 in which it tends to lower the head 51.

As already explained the spring 43 will force bearing 26 against conical head 40 and cause these parts to hold the remover R frictionally in the full line position shown in Fig. 11, but if the friction should slip slightly due to upward rebound incident to striking of the carrier 25 against the stop 65, the carrier will turn slightly in a clockwise direction, Fig. 2. Should this happen the rubber tube 51, tending to assume its normal shape, will change from the full line to the dotted line position of Fig. 11, but will continue to hold the head 52 down with hook or tongue 53 embedded in the pile material 18. Because of the resilience of tube 51 it will be seen that a moderate amount of rebounding of carrier 25 can occur without lifting the head 52 to a position in which it would miss the thread T.

When the remover R is down in thread pick-up position air passage 28 in tube 27 will be registered with port 44 in head 40, and subatmospheric pressures existing in the source 30 will cause a stream of air to flow into mouth 54 and forwardly through port 44 and into passage 41.

Bobbin transfer ordinarily occurs when the lay is at front center, or the position shown in Fig. 1, and as the lay moves rearwardly the thread T will be directed by tongue or lip 53 toward intake mouth 54 and be drawn pneumatically into the latter and along the interior of elastic tube 50 through air passage 28 and directly to and through port 44 into the passage 41 in pivot tube 22. At this time the remover and tube 22 are in the relative angular position shown in Fig. 5. The thong or resetter 60 will straighten from the slack position of Fig. 8 to the taut position of Fig. 9 as the lay moves to its back center position and rock the carrier 25 and other parts of the remover R

back to normal non-pick-up position with the passage 28 out of register with port 44 but in register with recess or restricted passageway 45 as shown in Fig. 4. The recess 45 has a cross-sectional area considerably less than that of port 44.

It will be noticed that when the parts are in the position shown in Fig. 4 the air stream moving downwardly in passage 28 will be deflected by the recess 45 in a direction circumferential of the tube 22 and will then pass through the port 44 and enter the tube 22 in a direction more or less tangentially, or at least directed to one side of the axis of the tube 22. Because of the direction in which the jet of air enters tube 22, and also because the air is drawn along the interior of tube 22, the jet moves in a more or less helical or swirling path the effect of which is to revolve the thread in the tube and direct it against the inner walls of the tube 22 to dislodge any lint or dust which may be drawn into and collect on the interior walls of the tube. When the invention has been made with the tube 22 transparent this rotary or revolving motion of the thread can be clearly seen. The thread also moves around in the recess 45 tending to clear it of lint.

At the time the thread is drawn into the remover it will be connected at one end to the cloth, and it is for this reason that the helically moving stream of air in tube 22 can revolve the thread. Several picks of the loom after the remover has returned to its non-pick-up position the thread will be cut at the cloth selvage and will then move through the remover R, tube 22 and hose 30 to some form of known thread collector (not shown). While recess 45 is shallow it should be deep enough to allow a knot in the thread to pass through it.

In the preferred form of the invention the recess is in the tube 22, but if desired it may be formed in the hub which carries the small metal tube 21. In the modification shown in Fig. 12 the bearing or hub 70 corresponding to bearing or hub 26 has an interior bearing surface 71 into which is cut a recess 72 registering with the air passage 28 and extending circumferentially around the bearing surface 71 so that when the parts are in their inactive or non-pick-up position a stream of air will follow the same general course as that already described in connection with Fig. 4. In the modified form of the invention the tube 73 will not necessarily have a recess similar to recess 44 cut in it, but in other respects it will be similar to tube 22, including a port 74 similar to port 44.

Fig. 10 illustrates in dotted lines how the tube 50 will bend upwardly if the remover should move down against the top of a misplaced shuttle, and shows in full lines how the remover will bend if struck by a forwardly moving shuttle. Since the tube 50 is made of resilient or elastic material it is evident that head 51 can move in any direction when striking or being struck by the shuttle. In the past pneumatic thread removers have been yieldable in a forward direction only and the pick-up head has not been mounted for universal movement.

From the foregoing it will be seen that the invention provides a pneumatic thread remover having the thread pick-up head 51 and carrier or positioner 25 connected by a resilient or elastic tube 50 which not only permits universal movement of the head but also acts to maintain the head in pick-up position even though the

carrier 25 should rebound slightly after being moved to pick-up or operating position. The link 33 is adjustable as to length and will ordinarily depress or rock the carrier 25 sufficiently to place the tube 50 under stress for the purposes already described. The tube 50, being hollow, forms part of the pneumatic system and is strong enough to hold the head 51 out of the path of the shuttle when the remover is in idle position. Furthermore, the tube 22 serves as a pivotal mounting for the remover R, and its conical head 40 and spring 43 tend to maintain a close frictional fit with the remover which reduces air losses to a minimum and tends to hold the remover in any position to which it may be moved. When the remover is in thread pick-up position its air and thread passage will register with the port 44 or 74, but when in non-pick-up position its air passage will be out of register with the port and air leaving the remover will travel along a circumferential recess and enter tube 22 or 73 in a direction at one side of their axes to set up a rotation of air which causes the thread to revolve and clean the recess and air passage. The plug 42 can be removed to clean any accumulation of lint or dust in the stationary tubular member which may not be loosened by the thread.

Having thus described the invention it will be seen that changes and modifications of the foregoing specific disclosure may be made without departing from the spirit and scope of the invention.

What is claimed as new is:

1. In a pneumatic thread remover mechanism for a weft replenishing loom having a thread remaining incident to a weft replenishing operation, a carrier movably mounted on the loom normally in inoperative position but movable to operating position and within which subatmospheric pressures exist when the carrier is in operating position, a hollow thread pick-up head having an intake mouth, a resilient tube normally supporting the pick-up head in non-pick-up position and supported by the carrier, means operating incident to a weft replenishing operation moving the carrier from the normal position thereof to the operating position thereof and effective to locate the head in thread pick-up position relatively to the weft thread and deform the tube from the normal shape thereof and cause the tube to tend to move the head beyond the pick-up position thereof with reference to the normal position thereof, and means tending to hold the carrier in the operative position thereof, said tube being effective incident to slight movement of the carrier from the operating position thereof toward the inoperative position thereof against the action of the last named means to hold the head in pick-up position due to the tendency of said tube to assume the normal shape thereof.

2. In pneumatic thread remover mechanism for a weft replenishing loom having a weft thread remaining along the lay incident to a weft replenishing operation of the loom, a carrier mounted for movement relative to the loom, means normally holding the carrier in inoperative position and tending to hold the carrier in any position to which the carrier is moved, a thread pick-up head having an intake mouth, a soft elastic tube in which subatmospheric pressures exist when the carrier is in operating position connecting the head and carrier and normally holding the head in inoperative position, said mouth communicat-

ing pneumatically with the interior of the tube, means effective on a weft replenishing operation of the loom moving said carrier from the normal inoperative position thereof to the operating position thereof and causing the carrier acting in cooperation with the tube to move said head against the lay to thread pick-up position relatively to said weft thread and causing the tube to be deformed from the normal shape thereof in such a direction as to tend to move the head against the lay, said carrier tending to rebound from the operative position thereof and the tube incident to rebounding of the carrier returning from the deformed shape thereof toward the normal shape thereof to maintain the head in thread pick-up position.

3. In pneumatic thread remover mechanism for a weft replenishing loom, a carrier movably mounted on the loom normally in inoperative position, a thread pick-up head having an intake mouth for the thread, a resilient tubular member within which subatmospheric pressures exist when the head is in thread pick-up position, said tube being supported by the carrier and supporting the head and normally holding the latter in inoperative position when the carrier is in inoperative position, the interior of the tube being in pneumatic communication with said mouth, and means operative incident to a weft replenishing operation of the loom to move said carrier relatively to the loom in a direction to move said tube and head toward the lay, said tube being deflectable laterally in the event that the head engages a misplaced shuttle.

4. In pneumatic thread remover mechanism for a weft replenishing loom having a weft thread extending along the lay thereof incident to a weft replenishing operation, a support fixed with respect to the loom, a carrier pivoted on said support normally in inoperative position but movable to operative position and having a hollow part in which subatmospheric pressures exist when the carrier is in operative position, a thread pick-up head having a thread intake mouth, a soft elastic tube supported by the carrier and supporting the head, the intake mouth communicating pneumatically through said tube with said hollow part of the carrier, and means operating incident to a weft replenishing operation of the loom moving said carrier relatively to said support to the operative position thereof in a direction to cause said tubular member to move the head to thread pick-up position with respect to said weft thread and continue to move said carrier after the head is in thread pick-up position to deform said tube, said tube in the event that the carrier moves from the operating position thereof toward the inoperative position thereof acting due to the tendency of said tube to resume the normal form thereof to hold the head in thread pick-up position.

5. A pneumatic thread remover for a weft replenishing loom, said remover comprising a carrier formed with a hollow part, a soft elastic tube supported by the carrier having the interior thereof communicating pneumatically with said hollow part, and a thread pick-up head supported by the tube and having an intake mouth communicating pneumatically with said hollow part of the carrier through said tube.

6. In a pneumatic thread remover for a weft replenishing loom having a pivotal support thereon, said remover comprising a carrier adapted for pivotal mounting on the support, a metallic tube forming part of the carrier, the latter having a

hollow part thereof communicating pneumatically with the interior of said tube, a soft elastic tube mounted on said metallic tube, and a thread pick-up head supported by the elastic tube and having a thread intake mouth communicating pneumatically through the elastic tube with the interior of said metallic tube.

7. In a pneumatic thread remover for a weft replenishing loom having a thread to be removed, a stationary tubular member having an air passage therein and in which subatmospheric pressures exist, a thread remover unit rotatable on the tubular member having an air passage therein leading transversely from said tubular member to a thread intake mouth in the unit remote from the tubular member, the latter having a laterally opening port therein registrable with said air passage, and mechanism operated by the loom moving the unit angularly on the tubular member to a position in which said air passage registers with said port preparatory to removal of the thread and thereafter turning the unit on the tubular member to a position in which the air passage is out of register with said port.

8. In pneumatic thread remover mechanism for a thread extending along the lay of a weft replenishing loom, a stationary tubular member extending in a direction generally parallel to the lay and having an air and thread passage therein extending along the axis thereof and in which subatmospheric pressures exist, a hollow thread remover having a thread intake mouth and an air and thread passage therein leading from the mouth to the tubular member, and means mounting the remover for angular motion about the tubular member toward and from the lay, the tubular member having a laterally opening port capable of registry with the air passage in the remover, said remover when moved about the tubular member toward the lay causing registry of the air passage with the port and when moved about the tubular member away from the lay causing the air passage to be out of register with said port.

9. In a pneumatic thread remover for a weft replenishing loom having a thread to be removed extending along a lay, a fixed tube in front of the lay extending in the direction of the length of the lay and in which subatmospheric pressures exist, a second tube disposed transversely of the fixed tube mounted for angular motion on the latter to be either in thread pick-up position or in non-pick-up position and having a thread intake mouth at the end thereof remote from the first tube communicating with an air passage in the second tube leading to the fixed tube, the stationary tube having a port opening laterally therethrough registrable with said air passage, and operating mechanism for the second tube moving the latter to pick-up position and causing said air passage to register with said port and thereafter moving the second tube to non-pick-up position in which said air passage is out of register with the port.

10. In pneumatic thread remover mechanism for a loom, a hollow member having an elongated thread and air passage therein in which subatmospheric pressures exist, a thread remover having a thread and air passage therethrough, and means between said air passages directing air moving from the passage in the remover into the passage in the hollow member transversely of the latter and to one side of the axis of the air passage therein.

11. In pneumatic thread remover mechanism

for a loom, a hollow member having an elongated thread and air passage therein closed at one end thereof through which air passes in a direction from said one end to the other end thereof, a thread remover having a thread and air passage therein, and means between said passage in the remover and said passage in the member adjacent to said one end of the latter defining an air passageway between the passages through which air is drawn from the passage in the remover into the passage in the member in a direction transverse of the latter passage and to one side of the axis thereof.

12. In a pneumatic thread removing system for a loom having a thread to be removed extending along a lay, said system having an intake mouth for the thread and a source of subatmospheric pressures, a stationary tubular member pneumatically connected to said source and having an air passage therein formed with a port opening laterally therethrough from the axis of said passage, a remover member mounted for angular movement on the fixed member and having an air passage therein with said intake mouth at the end thereof remote from the fixed member, and means causing a thread extending from the air passage in the remover through said port into the fixed member to revolve against the interior of the fixed member to clear the latter of lint, said means including a passageway in the system leading from said air passage in the remover member to the port and causing air to move through the port in a direction to one side of the axis of the air passage in the stationary member.

13. In a pneumatic thread removing system for a loom having a thread to be removed extending along a lay, said system having an intake mouth for the thread and a source of subatmospheric pressures, a stationary tubular member pneumatically connected to said source and formed with a port opening laterally therethrough from the axis thereof, a remover member mounted for angular movement on the fixed member and having an air passage therein with said intake mouth at the end thereof remote from the fixed member, one of said members having a recess therein communicating with the port and extending circumferentially therefrom, said members in one relative angular position causing the air passage to register with the port to enable air moving through the system to move a thread from the air passage directly through said port into the stationary tubular members, and said members when in a different relative angular position causing the air passage to register with the recess so that air moving through the system will move the thread along said recess to said port, said recess causing air moving therefrom through the port to be directed to one side of the axis of the stationary tubular member to impart a swirling motion to the thread causing the latter to revolve in the stationary member and remove lint from the interior thereof.

14. In a pneumatic thread remover for a weft replenishing loom having a thread to be removed extending along a lay, a fixed tubular member in front of the lay extending in the direction of the length of the lay and in which subatmospheric pressures exist, a second tubular member having an air passage therein disposed transversely of the fixed tube mounted for angular motion about the latter to be either in thread pick-up position or in non-pick-up position and having a thread intake mouth at the end of the air passage remote from the first tube, the sta-

tionary tube having a port opening laterally therethrough, one of said members having therein a recess communicating with and extending circumferentially from the port and of less cross sectional area than that of the port, and operating mechanism for the second tubular member moving the latter to the pick-up position thereof and causing said air passage to register with the port and thereafter moving the second tubular member to the non-pick-up position thereof to register said air passage with the recess.

15. In a pneumatic thread remover for a weft replenishing loom having a thread to be removed, a stationary tubular member in which subatmospheric pressures exist having a laterally opening port therein, a remover member having an air passage therein and mounted for angular movement on the first member to be either in thread pick-up position or non-pick-up position, the remover member having a thread intake mouth communicating with said air passage at the end thereof remote from the first member, the remover member when in thread pick-up position causing the air passage therein to register with said port and when in non-pick-up position causing the air passage therein to be out of register with said port, one of said members having a recess communicating with the port and having a cross sectional area less than that of the port and extending circumferentially of the member in which it is formed, and mechanism operated by the loom turning the remover member on the tubular member to the thread pick-up position thereof in which said air passage registers with the port and thereafter turning the remover member on the tubular member to non-pick-up position with said air passage out of register with the port and in register with the recess and the latter requiring air moving from the air passage into the tubular member to travel along the recess circumferentially of the tubular member and enter the latter in a direction to one side of the axis thereof.

16. In pneumatic thread removing mechanism for a weft replenishing loom having a thread extending along a lay, a stationary support, a tubular member fixed to the support and having a conical head on one end thereof, a pneumatic thread remover member having a bearing fitting the conical head, a spring between said support and the bearing holding the latter in close engagement with the head, said tube having a port opening laterally from the interior thereof, and said remover having an air passage therein, said bearing movable angularly on the tube to one position in which said port registers with the air passage and to another position in which the port is out of register with the air passage.

17. In pneumatic thread removing mechanism for a weft replenishing loom having a thread extending along a lay, a support, a tube secured to the support and having a conical head on one end thereof, said head having a laterally opening port communicating with the interior of the tube, a thread remover unit angularly movable on the tube and having a bearing fitting the conical head and having an air passage opening through the bearing for registry with the port, resilient means between the support and the remover unit holding said bearing of the latter in close fit with said head, and means turning the unit on the tube to cause registry of the port with the air passage and thereafter moving the remover unit relatively to the tube to a position

in which the port is out of register with the air passage.

18. In pneumatic thread removing mechanism for a weft replenishing loom having a thread extending along a lay, a support, a tube secured to the support having a conical head thereon at one side of the support, the smaller end of said head being toward the support, a thread remover unit rotatably mounted on the tube and having a bearing fitting said head, the latter having a laterally opening port communicating with the interior of the tube and the remover unit having an air passage therein registerable with said port, resilient means operatively interposed between the support and the unit holding the bearing of the latter in close fit with the conical head, and means turning the remover unit on the tube first to one position in which the port registers with the air passage and then to another position in which the port is out of register with the air passage.

19. A pneumatic thread remover unit for a weft replenishing loom, said unit including a support, a tubular member secured to the support and having a conical head at one end thereof through which extends a port communicating with the interior of the tubular member, a thread remover member pivotally mounted on the tubular member and having a bearing fitting said head and having an air passage therein leading from said head to a thread intake mouth, and a spring between the support and the remover member holding the bearing in close fit with said head, the remover member when in one angular position respect to the tubular member registering the air passage therein with said port and when in a different angular position with respect to the tubular member causing the passage therein to be out of register with the port.

20. A pneumatic thread remover unit for a weft replenishing loom, said unit including a support, a tubular member secured to the support and having a conical head at one end thereof through which extends a port communicating with the interior of the tubular member, a thread remover member pivotally mounted on the tubular member and having a bearing fitting said head and through which extends an air passage, and a spring between the support and the remover member holding the bearing of the latter in close fit with said head, the remover member when in one angular position with respect to the tubular member registering the passage thereof with said port and when in a different angular position with respect to the tubular member causing the passage therein to be out of register with the port, and a removable plug

closing the end of the tubular member adjacent to the head detachable from the latter to permit removal of lint from the interior of the tubular member.

21. A pneumatic thread remover unit for a weft replenishing loom, said unit including a support, a tubular member secured to the support and having a conical head at one end thereof through which extends a port communicating with the interior of the tubular member, a thread remover member pivotally mounted on the tubular member and having a bearing fitting said head and having an air passage therein leading from said head to a thread intake mouth, a spring between the support and the remover member holding the bearing in close fit with said head, and said head being formed with a shallow recess communicating with and extending circumferentially from said ports, the remover member when in one angular position with respect to the tubular member registering the air passage therein with said port and when in a different angular position with respect to the tubular member registering said passage with said recess.

22. A pneumatic thread remover unit for a weft replenishing loom, said unit including a support, hollow means secured to the support and having a conical head member at one end thereof through which extends a port communicating with the interior of the hollow means, a thread remover member pivotally mounted on the hollow means and having a bearing fitting said head and having an air passage therein leading from said head member to a thread intake mouth, a spring between the support and the remover member holding the bearing in close fit with said head, and one of said members having a shallow recess communicating with and extending circumferentially from said port, the remover member when in one angular position with respect to the tubular member registering the air passage therein with said port and when in a different angular position with respect to the tubular member registering the air passage therein with said recess.

GEORGE N. PETERSON.
